DRILLING MACHINE

Ralph Bender Mentzer, Lancaster, Pa., assignor
to Hamilton Watch Company, Lancaster, Pa.

Application June 11, 1941, Serial No. 397,566

14 Claims. (Cl. 51—131)

This invention relates to automatic drilling machines and has for its object the provision of means for and method of automatically accomplishing delicate drilling work.

Another object is to provide improved means and method of drilling jewels.

Another object is to provide automatic means adapted to bring about a plurality of relative approaches and retreats of the drill and workpiece during a single drilling operation.

Another object is to provide automatic means adapted to bring about a series of separate contacts, of increasing length, between the drill and the work, during a single drilling operation.

Another object is to provide automatic means adapted to bring about a plurality of relative approaches and retreats of the drill and workpiece during a single drilling operation, with the extent of the approaches and the length of time between the end of the approach and the beginning of the retreat progressively increasing.

Another object is to provide an automatic drilling device having means constantly tending to hold the drill and workpiece in contact and means adapted to periodically overcome that tendency during a single drilling operation.

Another object is to provide automatic means adapted to quickly bring about a relative approach between the drill and workpiece from a relatively great separation to a relatively small separation and thereafter a plurality of relatively slow approaches from the small separation position, all during a single drilling operation.

Other and further objects will be clearly apparent from the following specifications and from the drawings.

Fig. I is a plan view of the device embodying this invention;

Fig. II is a side elevation of the device illustrated in Fig. I;

Fig. III is an end elevation of the left portion of the device as illustrated in Fig. I;

Fig. IV is an end elevation of the right portion of the device as shown in Fig. I;

Fig. V is a section of the drill holder unit;

Fig. VI is a section of the work holder unit;

Fig. VII is an elevation of the member 70, of Fig. II;

Fig. VIII is an end view of cam 14, Fig. II; and

Fig. IX is a longitudinal central section of cam 14, Fig. II.

The drilling of small holes particularly in small relatively brittle objects such as timepiece jewels has been a difficult and delicate operation, requiring the constant and careful attention of a skilled

operator during its performance. The approach of the tool to the work, the pressure applied and the permissible length of actual drilling time at one stretch during the various stages of a single drilling operation, must be carefully and expertly governed and carried out. This makes for a time consuming and expensive operation.

The device of this invention obviates the prior art difficulties by providing automatic means for carrying out all of the difficult and delicate steps of the operation, and is such that a single, unskilled operator may efficiently run several machines simultaneously and accordingly a considerable savings in time and operation expense is effected.

The automatic drill of this invention is particularly directed to and adapted to the drilling of small pivot holes in watch jewels. For purposes of illustration and description, the invention is explained in connection with a jewel drilling machine. However, it should be clearly understood that this invention may be used in any drilling operation.

In order to impart strength and accuracy to the necessarily small diameter drill, it is rotated at a fast rate. The jewel is also rotated but at a slower rate, and abrasive is placed on the jewel and allowed to work into the hole being drilled.

The jewel is first set up in a holder separate from the drill and approximately concentric with the holder. The holder is then mounted in the drill concentrically with the work holder shaft. In this way the jewel is drilled at its approximate center and accordingly the procedure of later forming the periphery of the jewel concentric with the drilled hole is not only made easier and simpler, but less jewel stock is wasted than if the hole had not been drilled with such regard for concentricity.

Since the drill is delicate and the jewel hard, relatively slow approach of the drill to the work is effected. It is also necessary to keep the drill in contact with the jewel only a short period of time at first, in order to get the hole started without breaking the drill. As the drilling proceeds, the drill may be kept in contact with the jewel for progressively longer periods, as the hole gets deeper, and this is all accomplished automatically. The pressure of the work against the tool is made steady and resilient during its permitted periods through the action of a weight on a resilient lever, constantly tending to urge the work against the tool but periodically overcome by cam action.

The work is accordingly moved toward and

away from the tool a number of times during the drilling action and allowed to remain in contact with the tool between these motions for progressively increasingly periods of time as the hole gets deeper. It is not usually desirable to drill the hole all the way through the jewel, since one side is to be cupped in a later operation. Accordingly the extent of the drilling is automatically controlled to prevent excess drilling through material which is to be removed subsequently.

The whole device is automatic and needs only the depression of a single starting lever to start drill and work rotation as well as cam and feed operation.

The device embodying this invention comprises three units adapted to work together. These are, a work holder unit, a tool holder unit, and a control unit. The work holder unit includes a plate member 39 and a cap member 40, between which the work is adapted to be held. The tool holder unit includes a tool chuck 27, and the control unit includes cam 14, and feed screw 15.

This unit construction permits the several units to be removed or replaced separately and is an advantage when it is desired to repair or replace any of the parts of the device.

The work is rotated at a relatively slow speed as the plate member 39 and cap member 40 are rotated through the action of the motor 5 and the control unit by the agencies of the pulleys 6 and 7 and the belt 8.

The drill 26, held in the tool chuck 27, is adapted to be rotated at a relatively high rate of speed through the action of continuously traveling belt 10 on the drive pulley 12.

The motor 5 also operates a feeding arrangement for bringing the work holder into operative relation with the drill 26. This arrangement comprises mainly a cam lever 13, a cam 14 and a feeding screw 15. The feeding screw 15 is driven by the motor 5 through the worm gear 16 and the cam 14 is so contoured as to cause the work holder to be moved towards and away from the drill 26 in such a manner that the work holder is moved relatively slowly towards the tool holder and relatively quickly away therefrom several times during the operation of drilling one jewel. This method of operation is used since the drill used in this invention is of very small diameter and quite delicate and brittle so that the relative approach between the drill and the work must be slow and the drill must be held against the work only calculated and relatively short periods of time. The drill is then removed from the work before the operation is finished through the action of the cam 14 and cam lever 13 in order to permit abrasive to enter the partially drilled hole in the jewel and to prevent damage to the drill, and then the drill is again brought into contact with the work. The work holder is urged toward the drill by means of a weight 17 (Fig. I) which is adjustable longitudinally on a lever 18. The lever 18 acts through the work spindle operating lever 19, and is preferably formed of resilient material so that the jewel is held against the drill with a steady, yet resilient, pressure.

The device of this invention as illustrated in the drawings shows the various mechanisms and parts in their out of operation position, that is, with the device ready to start the drilling operation. The traveling belt 10 is constantly moving and rotating the idler pulley 11 but the drive pulley 12 is not yet in operation so that the drill spindle is stationary.

The drill spindle unit is illustrated in Fig. V and comprises a housing 20 in which a hollow shaft 21 is rotatably mounted at each end thereof on ball bearings 22. The shaft 21 has an exterior thread 23 at its upper end by means of which the drive pulley 12 is mounted thereon for rotation therewith. There is a second hollow shaft 24 mounted in the hollow of the shaft 21 and so mounted as to rotate with the shaft 21. 5 The shaft 24 has a head or finger piece 25 at one end thereof which extends beyond the hollow shaft 21 and pulley 12. The hollow of the shaft 24 is adapted to contain the drill 26. A chuck member 27 is threaded to the lower end of the shaft 24 and the drill is held in operative position by jaws 28 of this chuck. The chuck 27 may be loosened and the jaws 28 opened by turning the finger member 25, so that the drill may be moved to a new position in the chuck 27 and 10 the jaws 28 thereafter clamped on the drill. The drill is normally a relatively long member, and when its working end becomes worn, it is drawn through the chuck 27 and broken off to present a fresh drilling portion. The housing 20 is provided with an oil cup 29 near its top and an oil drain 30 near its base so that the bearings 22 are constantly properly lubricated.

The drill 26 is positioned in the chuck 27 so that its working end lies at a point in relation to the work holder which is effectively zero drilling position as governed by the contour and position of the cam 14 and feeding screw 15. The adjustment of the drill to this zero position is effected through the use of a stop member 31, see 15 Figs. I, II, and III. This stop member 31 is in the form of a substantially horizontal plate which may be swung into position between the drill and the work holder, by means of a handle 34, about its pivot 32 which is mounted on a bracket 33 supported by the housing of the work holder unit.

The drill is therefore moved through the chuck 27 until it contacts the plate 31, the jaws 28 of the chuck are then closed upon the drill through 20 the movement of the finger piece 25, and the plate 31 is thereafter pivoted out of the way of the drill. As well as acting as a stop and positioning member the plate 31 also acts as a protector for the work in the work holder. When the drill 26, after 25 a certain period of operation, becomes under size for a short portion of its length, this portion is broken off, usually with a pair of pliers, in order to present a new and fresh portion of the drill to the work. With the plate 31 in position between 30 the drill and the work there is no possibility of this small broken off piece of drill getting in the work holder or in a partially drilled hole in the work and causing damage.

The jewel to be drilled is held in a separate 35 holder which in turn is held between the plate 39 and cap 40 in the work holder unit. As illustrated in Fig. VI the work spindle 36 is rotatably supported in a sleeve 37 which is mounted in the work supporting unit. The spindle 36 is 40 driven through the pulley 7 which is rigidly attached thereto. In order to permit the insertion of the jewel holder in the work holding unit a hollow cap sleeve 38 is mounted over the spindle 36 and within the sleeve 37. The spindle 36 and sleeve 38 are adapted to rotate with each other 45 within the fixed sleeve 37 but are movable longitudinally relative to each other in order to permit the insertion of the jewel holder between the plate member 39 which is secured to the sleeve 38 and the cap member 40 of the spindle 36.

through one of the openings 46 in the sleeve 38. The cap member 40 has an initially centering portion 41 which is adapted to fit within a portion of the jewel holder so as to locate the holder substantially concentrically of the spindle 36. The centering of the jewel holder is completed when the bevel of the plate member 39 is forced against a bevel of the jewel holder to clamp the jewel holder between the plate 39 and the cap 40.

The plate 39 and cap 40 are separated to permit the insertion of the jewel holder therebetween through one of the openings 46 by the action of a cam member 42, see Figs. II and III, on the lower end of the shaft 43 which is positioned within the spindle 36. The shaft 43 rotates with and is movable longitudinally with respect to the spindle 36 and movement of the shaft 43 longitudinally against the action of spring 44 causes the sleeve 38 to move with respect to the spindle under the action of the cross pin 45 so as to separate the cap member 40 and the plate member 39 sufficiently to permit the insertion of the jewel holder therebetween through one of the openings 46.

The spring member 44 acts downwardly on a shoulder 47 of the shaft 43 and upwardly on a shoulder 48 of the spindle 36 so that the plate 39 and the cap member 40 are normally urged toward each other.

The cam member 42 is operable to lift the shaft 43 and separate plate 39 and cap 40 through its association with a horizontally disposed lever 49 pivotally mounted at 50 on the housing of the work holding unit.

The cam 42 is so formed and mounted as to straddle the lever 49 so that when this lever is moved about its pivot 50 by means of the handle 51 the cam is correspondingly caused to move against the lower end of the shaft 43 and cause the shaft 43 to ride on this cam 42 to move the shaft 43 up or down as desired.

The spindle 36 is normally kept from rotating through the action of the detent 52 upon a sleeve 53 which is rigidly secured to the spindle 36. The sleeve 53 is provided with V slots 54 into which the tapered end 55 of the detent 52 is forced by a spring 56. The spring 56 and detent 52 are mounted in an opening in the work holder housing. The spindle 36 and accordingly the work holding assembly are, by this arrangement, located in such a position as to present, when stationary, one of the openings 46 at the front of the machine to facilitate the insertion of the jewel holder.

The operation of the device as a whole is started by downward pressure on the finger piece 57 of the starting lever 58. This lever is mounted for vertical movement about a horizontal pivot 59 in the housing of the control unit. When the lever 58 is depressed about its pivot 59 several actions take place simultaneously. The spindle 36 is released so that it may be rotated, the drill 26 is caused to be rotated through the action of the traveling belt 10, the motor 5 is started and caused to rotate the work spindle 36, and the cam 14 and feed gear 15 are brought into action to move the work toward and away from the drill 26.

The spindle 36 is released when the detent 52 is moved out of contact with the sleeve 53 against the action of the spring 56 by means of a cam member 60 which is moved downwardly upon the depression of the starting lever 58 through its connection 111 therewith. The cam member 60 moves in a slot 62 in the detent 52 to force the detent 52 away from the sleeve 53 so that the spindle 36 is then free to rotate. The spring 63 75

constantly tends to move the starting lever 58 upwards about its pivot 59.

The drill 26 is brought into rotation upon the depression of the starting lever 58 by the release of the angle lever 64 from its contact with the cam member 65. The angle member 64 is pivoted on the housing of the drill spindle unit at 66 and has one leg 67 which supports the idler pulley 11 and another leg 68 which is adapted to contact the cam 65 so as to hold the idler pulley 11 away from the drive pulley 12 against the action of the spring 69.

The cam 65 is mounted on a plate 70 for sliding movement vertically of the housing of the drill unit by means of bolts 115 located in elongated openings 116 in the plate 70, and is connected to the starting lever 58 at 61 through a connecting arm 111 which is attached to the plate 70 at 112 so that depression of the lever 58 moves the cam 65 downward and out of contact with the leg 68 and permits the spring 69 to draw the idler pulley 11 towards the drill driving pulley 12 so as to cause the belt 10 to act upon the pulley 12 to drive the drill 26. Releasing of the starting lever 58 causes the cam 65 to move upward, under the action of spring 63 which encircles the continuation 113 of the plate 70 and which presses upwards against the plate 70 and downwards against the housing 114, against the leg 68 of the angle piece 64 and separate the belt 10 and the drive pulley 12 and consequently stop the drive of the drill. The belt 10 is under such pressure against the idler pulley 11 that the belt will follow the idler as it moves away from the drive pulley 12.

The idler pulley 11 is mounted on the angle piece 64 by means of a bearing screw 71 and operates on bearing 72 and is provided with a cap member 73.

The motor 5 is brought into operation upon the depression of the starting lever 58. This is accomplished through a spring member 74 mounted on the lever 58 and pressing against the contact of the starting switch 75 normally holding the switch in open position. The downward movement of the lever 58 relieves the pressure of the spring 74 on the switch contact and permits the circuit to close, thus starting the motor. It will also be seen that when the lever 58 is raised, the spring again exerts pressure upon the switch contact and opens the circuit, thus automatically stopping the motor.

The spindle 36 of the work holder unit is adapted to be raised and lowered so as to move the work toward and away from the drill 26 under the action of lever 19. The lever 19 has one end fixedly mounted on a horizontal shaft 76 pivotally mounted in the housing 114. The other end of the lever 19 is adapted to move the spindle 36 upward and downward through the action of a pin 77, mounted in the end of the lever 19, upon the bushing 78 or the sleeve 53. The shaft 76 is constantly urged about its axis by means of the lever 18 and the weight 17 thereon in such a direction as to urge the work holder upward towards the drill. The motion of the work holder toward and away from the drill is, however, controlled by the cam shaft 13 which also has one end fixedly mounted on the shaft 76. The cam shaft 13 at its other end has a cam nose 79 which bears on the cam 14 and through the connection with the shaft 76 and the fixed connection of the arm 18 with the shaft 76 the weight 17 acts not

only to urge the work holder upward but also to urge the cam nose 79 against the cam 14.

Accordingly, the cam nose 79 is adapted to follow the contours of the cam 14 during rotary and longitudinal movement of that cam except in some instances during the operation of the device. The cam 14 is so shaped that at certain portions thereof, namely, the low points of the flutes 81, see Figs. I, II and VIII, the cam nose 79 will not be in contact with the cam because of the fact that the work is in contact with the tool under the pressure of the weight 17.

The cam 14 has a two way action. As it is moved longitudinally of its own axis the cam nose 79 is caused to travel down the face 82 of the cam and move the work at a relatively rapid rate to a point, as represented on the cam at 83, just short of being in contact with the drill. Meanwhile the cam 14 is rotated so that the nose 79 moves circumferentially thereon in and out of the flutes 81 causing the work to move towards and away from the drill. As the cam nose 79 moves down the gradual slope as indicated at 84 the work is moved gradually towards the drill and then as the cam nose moves up the sharp slope 85 of the cam 14 the work is quickly dropped away from the drill.

An important feature of this invention is the combined operation of the weight 17 and the cam 14 in their control of the movements of the work with respect to the tool.

The nose 79 of the cam lever 13 is urged against and caused to follow the contours of cam 14 through the action of the weight 17 which is mounted on resilient lever 18 in such a way as to tend to rotate shaft 16 and move lever 13 down, and lever 19, and accordingly the work holder, up.

Thus, when the work is not in contact with the drill, it will be moved in accordance with the movement of the nose 79 on the cam 14, so that the action of the cam most of the time is to keep the work away from the drill. When the nose 79 moves into one of the depressions 81 in the cam 14 the work is brought into contact with the tool. Since the cam keeps moving, its rotation leaves the cam nose 79 temporarily hanging in the air between the high points of the cam. This is so since the lever 19 is prevented from moving upward by the contact of the work and the tool and accordingly the lever 13 is prevented from moving downward.

In this position the work and the tool are urged against each other with a force provided by the weight 17 and a resilience provided by the weight lever 18. The work and tool are thus permitted to contact each other for a length of time determined by the speed of rotation of the cam 14 and the pitch and speed of rotation of the feed screw 15. As the cam rotates, the cam lever nose 79 is again picked up on a shoulder of the cam as at 85 in Fig. VIII which, as the cam continues to revolve, lifts the nose 79 and moves the work away from the tool against the action of the weight 17. As is shown in Fig. II, the grooves 81 of cam 14 are substantially V shaped with the small point of the V near the starting position of the cam with respect to the starting of the drilling operation. This V slot or groove in the cam becomes wider and deeper as the drilling proceeds. The depth of the groove 81 permits the work to be moved further and further upwards as it progresses and as the hole is drilled and the width of the groove permits the drill to stay in contact with the work longer and

longer periods of time as the drilling goes on and the hole gets deeper.

The double action of the cam is set into operation when the starting lever 58 is depressed. The 5 housing of the control assembly has a bell crank lever 86 pivotally mounted therein at 87. The lever 86 has one leg pivotally attached to a connection shaft 88 which is also pivotally attached to the starting lever 58. The other leg of the 10 bell crank lever 86 is connected through a yoke member 109 to a collar 110 which is movable longitudinally of and is mounted on the supporting shaft 89 of the cam 14 and feed screw 15. When the starting lever 58 is depressed the bell crank 15 lever 86 is moved about its pivot 87 and causes the cam 14 and the feed screw 15 to be moved along their supporting shaft 89 against the action of the spring 90 which is also mounted on the shaft 89. The shaft 89 is rotated by the 20 motor 5 through the worm gear 16, and the feed screw 15 and cam 14 are so keyed to the shaft 89 as to rotate with it and be movable along it.

The starting lever 58 supports a bracket 91 in 25 which a headed pin 92 is vertically positioned. The pin 92 is of such a contour as to relatively closely and slidably fit within the opening between the bracket 91 and the lever 58, and the head of the pin 92 is of such a size as to prevent the pin from dropping through the opening 30 formed by the bracket 91. The pin 92 is urged downwardly by a spring member 93 which is mounted on the starting lever 58 and presses downwardly against the head of the pin 92.

The pin 92 has at its lower end a finger 94 35 which is adapted to fit within and travel along the threads of the feed screw 15 upon the rotation of the shaft 89. When the lever 58 is depressed the cam 14 and feed screw 15 are so moved along their axis 89 and the finger 94 of the pin 92 is so moved downwardly as to bring the finger 94 into contact with the feed screw 15 so that continued rotation of the feed screw 15 causes it and cam 14 to be drawn along their shaft 89 against the action of spring 90, because 45 of the riding contact of the finger 94 with the feed screw 15, and accordingly the cam nose 79 travels over the contours of the cam 14 longitudinally and circumferentially as the rotation of the shaft 89 continues.

The spring 93 presses downwardly on the pin 92 so that in the event the finger 94 does not immediately fall within the thread of the feed screw 15, the pin 92 may be pushed upward against the spring 93 until such time as it does fall into the 55 thread. This prevents breakage or damage to the finger 94 or the threads of the feed screw 15.

The lever 58 is maintained in its depressed or operating position by means of a holding lever 95 which is pivoted to the housing of the control 60 assembly at 96. A holding bracket 97 is mounted on the starting lever 58 and when the starting lever 58 is in its raised position, as shown in the drawings, the holding lever 95 is pulled against the bracket 97 under the action of spring 98 which has one end attached to the starting lever 58 at 99 and the other end attached to the holding lever 95 at 100. This side pressure has no downward holding effect on the lever 58 but merely keeps the holding lever 95 in readiness for operation. When the starting lever 58 is depressed the spring 98 pulls the holding lever 95 so as to cause the surface 101 of the bracket 97 to be held beneath and by the surface 102 of the holding 70 lever 95. Thus the starting lever 58 is prevented

from moving upwardly about its pivot 58 under the action of the spring 63.

While the starting lever 58 is held down by the holding lever 95 the finger 94 travels in the threads of the feed screw 15, thus causing the drilling to proceed. The extent of the drilling, that is, the length of time which it is allowed to continue, may be automatically set by means of the stop pin 103. This pin is adjustably mounted on the holding lever 95 and is adapted to contact the face 104 of the cam 14 when the cam has been moved along its axis toward the finger 94 the desired amount.

When the pin 103 contacts the surface 104 of the cam 14, continued movement of the cam along its axis will push the holding lever 95 about its pivot 96, and separate the holding surfaces 101 and 102 of bracket 97 and holding lever 95 respectively. The starting lever 58 will then rise under the action of the spring 63. The drilling operation will consequently stop since the spring member 74 again presses on the contact of the switch 75, opening the motor circuit and stopping the motor 5. Also, the upward movement of the starting lever 58 moves the cam 65 upward against the leg 68 of the angle piece 64 so as to move the idler pulley 11 and the belt 10 away from the drive pulley 12, thus stopping the driving of the drill.

The motor 5 being stopped, the work holder spindle is no longer driven, and the upward movement of the starting lever 58 moves the cam 60 out of contact with the pin 52 which is accordingly again pressed against sleeve 53 under the action of the spring 56 and the coasting of the spindle 36 turns the sleeve 53 until one of the V slots 54 therein is contacted by the end 55 of the pin 52 so as to hold the work holding spindle 36 in one of the loading positions as determined by the positions of the openings 46. This is possible since the work spindle is no longer driven by the motor. Also the cam 14 and the feed screw 15 are moved back to their original starting position, which is shown in Fig. II, under the action of the spring 90, as soon as the pin member 94 is removed from the threads of the screw member 15 by lifting the starting lever 58 and, as they are no longer urged along their axis through the action of the bell crank lever 88.

When the cam member 14 and feed screw 15 are snapped back into starting position by the spring 90 they are stopped by means of a resilient type washer 105 of material such as leather, or other suitable cushioning means.

Emergency stop means is provided in the form of a rod 106 which is suspended beneath and along the length of the starting lever 58. The rod 106 is operable through a push button 107, adjacent and below the starting button 57. Pushing the button 107 causes the rod 106 to engage the holding lever 95 so as to separate the holding surfaces 101 and 102 whereby the starting lever 58 will move upwardly and the machine will stop. The emergency lever 106 is held in its normal inoperative position by spring member 108.

What I claim is:

1. In an automatic drilling machine, a drill, a workholder, means adapted to bring about a plurality of periodic contacts of said drill with work in said workholder during a single drilling operation, and means for progressively increasing the duration of contact of said periodic contacts.

2. In an automatic drilling machine, a drill, a workholder, said workholder adapted to hold the

work upon which the drill operates, means adapted to produce a plurality of relative movements between and periodic contacts of, the drill and the work, the movements of the drill and workholder being toward and away from each other and means progressively increasing the duration of said periodic contacts between the drill and the work during the period of a single drilling operation.

3. In a device of the character described, a cam member mounted for simultaneous rotary and axial movement on its own longitudinal axis, and a follower for said cam member, said cam being adapted to cause its follower to periodically move from the same effective zero position in progressively increasing lengths of movement and to periodically rest for progressively increasing periods of time.

4. In an automatic drilling machine, a drill, a workholder, and control means adapted to bring about a plurality of periodic contacts of said drill with work in said workholder during a single drilling operation, and with said contacts progressively increasing in duration of contact, said control means including a cam adapted to move along, and rotate about, its longitudinal axis, and a feed screw adapted to aid in moving said cam along said axis.

5. In an automatic drilling machine, a drill, a workholder having work supported therein, control means adapted to bring about a plurality of periodic contacts of said drill with said work during a single drilling operation, and with said contacts progressively increasing in duration of contact, said control means including a cam adapted to move along, and rotate about, its longitudinal axis, and a feed screw adapted to aid in moving said cam along said axis, and resiliently supported weight means adapted to resiliently urge said work against said drill during the periods of said contacts.

6. In an automatic drilling machine, a drilling chuck, means for revolving said chuck, a drill rod adjustably carried in said chuck, a work holder having a jewel carried thereby, a vertically movable rotatable support for said work holder, means for forcing said jewel into a predetermined number of periodic contacts with said drilling rod, means for progressively increasing the duration of contact of said periodic contacts, and means for stopping the drilling operation upon completion of the predetermined number of contacts.

7. In an automatic drilling machine, a drilling chuck, means for revolving said chuck, a drill rod adjustably carried in said chuck, a work holder having a jewel carried thereby, a vertically movable rotatable support for said work holder, a rotatable cam mounted for longitudinal movement, a pivoted lever bearing upon the cam at one end and engaging the rotatable support at the other end, means for resiliently forcing said support into engagement with said lever whereby said cam causes the rotatable support to be raised and lowered to bring the jewel into periodic contact with said drill, means for progressively increasing the duration of contact of said periodic contacts, and means for controlling the number of said contacts.

8. In an automatic drilling machine a rotatable drill formed of an unsharpened iron wire, a drilling compound, a work support carrying a work piece mounted for vertical movement, a weight, a cam normally urging said workpiece into contact with said drill, having a series of

upstanding projections, said projections tapering from a base to an apex, longitudinal of said cam surface, means for rotating and moving said cam longitudinally, a lever contacting the projections of said cam surface and controlling the vertical movement of said work support, the longitudinal and rotational movement of said cam permitting the weight to force the work support into a series of periodic contacts with said drill, said contacts progressively increasing in duration during the 10 drilling operation.

9. In an automatic drilling machine, a rotatable drill formed of an unsharpened iron wire, a drilling compound, a work support carrying a workpiece and mounted for vertical movement, 15 a weight yieldingly urging said workpiece into contact with said drill, a cam having a series of upstanding projections, said projections tapering from a base to an apex, longitudinal of said cam surface, means for rotating and moving said 20 cam longitudinally, a lever contacting the projections of said cam surface and controlling the action of said work support, the longitudinal and rotational movement of said cam permitting the weight to force the work support into a series of 25 periodic contacts with said drill, said contacts progressively increasing in duration during the drilling operation and adjustable means for limiting the drilling operation.

10. In an automatic drilling machine according to claim 9 the drilling limiting means comprising a stop controlled by the longitudinal movement of the cam.

11. In an automatic drilling machine having a workpiece movable in a vertical plane, a drill, 30 means for moving said workpiece toward and

away from said drill and into contact with said drill, means for progressively increasing the duration of contact between said workpiece and said drill during a single drilling operation and stop means to stop the drilling operation upon the completion of a predetermined number of said contacts.

12. In an automatic drilling machine having a workpiece movable in a vertical plane, a drill, means for moving said workpiece toward and away from said drill, a cam controlling the vertical movement of said workpiece and means controlling the movements of said cam to progressively increase the duration of contact between said drill and said workpiece during a single drilling operation.

13. In an automatic drilling machine, a drill, a workholder having work mounted therein, means adapted to bring about a plurality of relative movements between said drill and said workholder toward and away from each other during the period of a single operation, and means for progressively increasing the duration of contact between said drill and said work.

14. In an automatic drilling machine, a drill having work piece supporting means, said workpiece having a jewel supported therein, means adapted to bring about a plurality of relative movements between and periodic contacts of, the drill and the jewel, with said movements being toward and away from each other means progressively increasing the duration of contact of said periodic contacts between said drill and said jewel during a single drilling operation.
